UNITED STATES PATENT OFFICE.

HENRY C. HALEMEYER, OF BRUSSELS, ILLINOIS.

MUSIC-LEAF TURNER.

Application filed July 14, 1927. Serial No. 205,734.

This invention relates to what is known in the art as a music leaf turner and the embodiment herein shown and described has more particular reference to a device of this class which is more especially designed for turning the loose leaf in sheet music such as is employed in piano playing.

As is well known, the ordinary sheet music embodies a cover page on the inner side of which a portion of the musical notation appears, usually the preliminary part of the verse; a back sheet containing the concluding part of the score, and the finale, and a loose leaf on opposite pages of which the remainder of the composition is scored.

In playing this class of music, the performer is compelled to turn the loose leaf back and forth when repetitions of the verse are required. As before stated, the present leaf turner is expressly designed for use in connection with this character of music, although it may be slightly varied for turning a multiplicity of sheets such as is used in orchestrations.

Briefly, it comprises a rack which is stationary, a single leaf turner which is mounted for swinging movement thereon, a foot pedal, and an operating connection between the foot pedal and the leaf turner.

The alleged novelty is based upon the novel arrangement and association of parts, which cooperate to produce a specifically new structure.

In the drawings:—

Figure 1 is a front elevation of an ordinary piano equipped with the device.

Fig. 2 is a bottom plan view of the device removed.

Fig. 3 is a vertical section through a portion of the rack.

Fig. 4 is an enlarged fragmentary detail and sectional elevational view of the lower left hand corner of the rack and the operating mechanism associated therewith.

Fig. 5 is a perspective view of the major part of the removable leaf turner.

Fig. 6 is a perspective view of one of the details.

Referring now to the drawings in detail, it will be seen that the reference character 7 designates generally the rack. This comprises a frame including a base member having a forwardly projecting horizontal extension 8 constructed to provide a ledge for reception of the music sheets. Connected to

and rising vertically from the base member are vertical backing bars 9 fastened at their upper ends to a horizontal top member 10. Supporting and foot blocks 11 are fastened to said base member 8, one of the blocks being represented in Fig. 6.

Incidentally, the block is of the shape shown, and preferably provided with a tapered end carrying a rubber buffer 12.

Rockably or swingably supported on the rack is the leaf turner generally designated by the reference character 13. This is in the form of a wire member which includes a vertical shaft 14 mounted for oscillation in suitable guide holes formed in the top and base members of the frame.

The lower end of the shaft 14 is formed to provide a crank 15 and the upper end is formed to provide an offset angularly disposed arm 16 which is equipped with resilient grips 17 constructed to engage the loose leaf (not shown) of the sheet music. As shown in Fig. 2, a link 18 is connected to the crank arm and extends through an opening formed in one of the blocks 11.

A coiled spring 19 is connected to this link and anchored on the rack as shown in Fig. 2. This serves to return the turner to a normal position as shown in Fig. 1. Connected to the link is a pull cord 20 which extends down over a small pulley 21, fastened on the outer bifurcated end of an extension member 22. As represented in Fig. 4, this member 22 is fastened by suitable means to one of the blocks 11. Also if desired, it may be formed intermediate its ends with a spacer and rest 23.

In considering Fig. 4, it will be noted that one end portion of the aforesaid link 18 is turned upwardly as indicated at 24 to insure smooth operation of the pull cord.

Considering again Fig. 1, it will be noticed that the pull cord extends down over a second pulley 25 then down over a third pulley 26, carried by a right angular bracket. Finally, it is connected with a pivotally mounted foot pedal 27 carried by a suitably anchored base plate 28.

The pedal is located within convenient operating distance of the performer's foot. In practice, the sheet of music (not shown) is placed upon the ledge 8 of the rack in an obvious manner and the spring clips are engaged with the central or loose leaf, the back sheet and cover page being spread open.

ready for playing. At this time, the loose leaf, is placed against the back sheet in the usual manner. However, when the end of the notation on the bottom of the page (usually page 2) is reached, the operator places his foot upon the pedal 27 and presses downwardly, swinging the turner over in a direction from right to left through an approximate half circle and turning the sheet over to expose the notation on the next page.

The operator must hold his foot on the pedal to hold this page over, while it is being played, and also while the notation on the back page is being read. However, when the end of the composition is reached, and a repeat is necessary, the foot is removed from the pedal and the spring serves to return the sheet to the normal relationship.

Persons familiar with inventions of this class will doubtless be able to obtain a clear understanding of the construction and method of use when considering the description in connection with the drawings. For this reason a more lengthy description is believed unnecessary.

Having thus described my invention, what I claim as new is:—

In a music leaf turner of the class described, a music sheet rack comprising a frame embodying a base member including a right angularly disposed horizontal sheet supporting ledge, a top member and longitudinally disposed vertically arranged connecting and backing members between and connected with said base and top members respectively, the two last-named members of said rack being formed with vertically alined bearing openings, a music leaf turner embodying a vertical shaft mounted for oscillation in said bearing openings, and including a horizontal top arm and a bottom crank arm disposed beneath said ledge, leaf engaging clips carried by and depending from said top arm, an operating link slidably supported upon said rack and connected with the crank arm, and manually manipulated operating means for said link.

In testimony whereof I affix my signature.

HENRY C. HALEMEYER.
